UNITED STATES PATENT OFFICE.

MARTHA L. SISSON, OF WASHINGTON, DISTRICT OF COLUMBIA.

EGG-CASE FILLER.

1,360,808.

Specification of Letters Patent. Patented Nov. 30, 1920.

Application filed February 16, 1920. Serial No. 358,929.

To all whom it may concern:

Be it known that I, MARTHA L. SISSON, a citizen of the United States, residing at Washington, District of Columbia, have invented new and useful Improvements in Egg-Case Fillers, of which the following is a specification.

This invention relates to egg-case fillers, and more specifically to a cell forming combination of elements to receive eggs in its cells for shipment in an egg-case or box.

The main object of this invention is to generally improve upon devices of this character by the provision of an improved construction and arrangement which is exceedingly efficient in protecting the eggs against breakage, and which is very convenient, strong, durable, and can be manufactured and maintained at a comparatively slight cost.

A further object is to provide an improved egg-case filler comprising a plurality of superposed bridge-like sets of egg-supports, each set including a spacing flange which is integral with the egg-supporting plate of this set, so that each set is automatically spaced from the other sets during the operation of placing the sets of fillers in the case or box.

Other objects and advantages are pointed out or implied in the following details of description, in connection with the accompanying drawings in which,—

Figure 1 is a vertical sectional view through a box or case and through my improved filler, the eggs being indicated in dotted lines.

Fig. 2 is a sectional view along the line 2—2 of Fig. 1, viewed in the downward direction as indicated by the arrows.

Referring to these drawings in detail, in which similar reference characters correspond with similar parts throughout the several views, and in which the box 1 may be of any appropriate kind, shape and size, the invention consists in the construction and arrangement of parts which will now be described as follows:

Each of the superposed bridge-like egg-supports or containers is exactly like the others with the slight exceptions which will be pointed out hereinafter. Therefore, a broad or limited description of one will suffice for each. The bottom 1^a of the box supports the lowermost one of the egg-supporting plates 2 through the medium of a down-

turned flange formed on this plate, this flange preferably extending throughout the margin of the plate 2. The down-turned flanges of the other plates 2 may be (though not essentially) wider than that of the lowermost plate 2. A set of strips 4 intersects a set of strips 5, and these strips may be secured together in any known or appropriate way so as to form separate egg-containing compartments, and these compartments are seated on the plate 2; that is, the strips are placed edgewise on the plate 2 and combine with the latter to form egg-cells. Egg-receiving apertures 2^a are provided in the plate 2, and the small ends of the eggs are seated therein and supported by their margins as shown in the drawings, these apertures being circular and relatively small so that the egg is supported a considerable distance above the floor 1^a.

The subcover for each set of cells consists of a relatively thin and flexible sheet 6 which is somewhat springy and is provided with openings 7 and with flexible and somewhat springy fingers or tongues 8 which extend inwardly of these openings and normally incline upwardly to form a seat for the larger end of an egg. These tongues press the egg yieldingly into the apertures 2^a and also compensate for the different sizes of eggs. A relatively rigid and thick plate 9 forms a supercover for this set of cells, holding the subcover against upward movement with the exception of the tongue 8.

The down-turned flange 2 of each superjacent set of cells rests on the relatively rigid plate 9 of the next subjacent set of cells, thereby supporting the superjacent set in spaced relation to the subjacent set, while the main portion of each set spans the interior of the box from wall to wall and provides a bridge-like egg-support which is somewhat yieldable and springy so as to cushion any shock received by the box and thus reduce the breakage of eggs to the minimum.

In addition to the features and elements thus far described, the uppermost set of cells is provided with an upturned flange 10 which extends to the cover 1^b of the box and spaces the eggs of this set of cells from the cover 1^b. The upturned flange 10 is formed integrally with the uppermost plate 9, whereas none of the other plates 9 are provided with a marginal flange. Each of the plates 9 is provided with relatively large ap-

ertures 11 through which the tongues 8 are pressed by the eggs on which they press.

For the sake of comparative lightness, cheapness and other desirable qualities, the plates 2 and 9, or either of them, may be formed of corrugated board, though the invention is not limited to the use of any specific material. Neither is the invention limited to the specific construction and arrangement shown and described, but changes may be made within the scope of the inventive ideas as implied and claimed.

What I claim as my invention is:—

1. In an egg-case filler, the combination of an egg-supporting plate formed with egg-receiving openings and with down-turned supporting edges, two sets of intersecting strips seated edgewise on said supporting plate and co-acting therewith to form egg-receiving compartments, a relatively flexible and thin sheet provided with egg-engaging tongues which are relatively flexible and springy, said sheet being seated on said intersecting strips, and a relatively rigid plate 20 provided with apertures through which said tongues are upwardly and inwardly inclined, this relatively rigid plate being seated on said relatively flexible plate for the purpose specified.

2. The combination defined by claim 1, and said relatively rigid plate having a flange formed in one piece therewith and extending entirely therearound and projecting upward for abutting against the under side of the top of a box, as specified.

3. The combination of a box including a floor and a cover; a plurality of superposed sets of egg-cells in said box, each of said sets comprising an egg-supporting plate formed with egg-receiving openings and with a 40 downturned supporting flange, the lowermost one of which rests on said floor and supports the remainder of this plate in spaced relation to said floor, two sets of intersecting strips seated edgewise on said supporting plate, a relatively flexible sheet formed with egg-engaging tongues and being seated on said intersecting strips, a relatively rigid plate seated on said relatively flexible sheet and provided with apertures receiving the 50 flexible tongues of said sheet, and an upturned flange formed on and extending substantially throughout the margin of the uppermost one of said relatively rigid plates 54 in position to abut against the under side of 55 said cover, for the purpose specified.

MARTHA L. SISSON.
